UNITED STATES PATENT OFFICE

HARRY F. DUNCAN, OF WASHINGTON, DISTRICT OF COLUMBIA, ASSIGNOR TO LITTLE TAVERN SHOPS, INC., OF WASHINGTON, DISTRICT OF COLUMBIA, A CORPORATION OF KENTUCKY

DESIGN FOR A DISPLAY CABINET

Application filed February 18, 1933. Serial No. 47,250. Term of patent 14 years.

To all whom it may concern:

Be it known that I, HARRY F. DUNCAN, a citizen of the United States, residing at 4807 Colorado Avenue, N. W., Washington, District of Columbia, have invented a new, original, and ornamental Design for Display Cabinets, of which the following is a specification, reference being had to the accompanying drawing, forming a part thereof.

The drawing shows a perspective view of the display cabinet.

I claim:

The ornamental design for a display cabinet, substantially as shown.

HARRY F. DUNCAN.
